CLAIM

The ornamental design for a lamp, as shown and described.

DESCRIPTION

FIG. 1 is a perspective view of an embodiment of the ornamental design of the lamp.

FIG. 2 is a perspective view of another embodiment of the ornamental design of the lamp.

FIG. 3 is a top view of an embodiment of the ornamental design of the lamp.

FIG. 4 is a top view of an embodiment of the ornamental design of the lamp.

FIG. 5 is a side view of an embodiment of the ornamental design of the lamp.

FIG. 6 is a front/back view of an embodiment of the ornamental design of the lamp.

FIG. 7 is a bottom view of an embodiment of the ornamental design of the lamp.

FIG. 8 is another perspective view of an embodiment of the ornamental design of the lamp.

FIG. 9 is a perspective view of another embodiment of the ornamental design of the lamp.

FIG. 10 is a top view of another embodiment of the ornamental design of the lamp.

FIG. 11 is a side view of another embodiment of the ornamental design of the lamp.

FIG. 12 is a front/back view of another embodiment of the ornamental design of the lamp.

FIG. 13 is a bottom view of another embodiment of the ornamental design of the lamp; and,

FIG. 14 is another perspective view of another embodiment of the ornamental design of the lamp.

The broken-line disclosure in the views is understood to represent portions of the article in which the claimed design is embodied, but which form no part of the claimed design.
